Primary Examiner — Philip S Hyder*Assistant Examiner* — Roselynne Cody*(74) Attorney, Agent, or Firm* — Cantor Colburn LLP(57) **CLAIM**

I claim, the ornamental design for a rescue tool, as shown and described.

DESCRIPTION

FIG. 1 is a top plan view of a rescue tool, showing my new design;

FIG. 2 is an elevation view of a first side thereof;

FIG. 3 is a bottom plan view thereof;

FIG. 4 is an elevation view of a second side thereof;

FIG. 5 is an elevation view of a third side thereof, opposite from that shown in FIG. 2;

FIG. 6 is an elevation view of a fourth side thereof, opposite from that shown in FIG. 4;

FIG. 7 is a perspective view thereof; and,

FIG. 8 is an exploded perspective view thereof.

The broken lines showing in FIG. 8 are directed to a feature of the tool that forms no part of the claim.
